UNITED STATES PATENT OFFICE.

WILLIAM WUTHENOW, OF NEW YORK, N. Y.

DESIGN FOR A PHONOGRAPH-BOX OR SIMILAR ARTICLE.

42,569.

Specification for Design.

Patented May 28, 1912.

Application filed October 28, 1911. Serial No. 657,390. Term of patent 14 years.

To all whom it may concern:

Be it known that I, WILLIAM WUTHENOW, a citizen of the United States, residing in the borough of Manhattan, city, county, and State of New York, have invented a new, original, and ornamental Design for Phonograph-Boxes or Similar Articles, of which the following is a specification, reference being had to the accompanying drawing, which forms a part of this application, and in which—

Figure 1 is a top rear perspective view of a box embodying the design; Fig. 2 is a top plan view of the same; and Fig. 3 is a side elevation of the same looking in the direction of the arrow accompanying Fig. 2.

The contour of the box in plan view is substantially triangular. From every point

of view in elevation the contour of the box is substantially rectangular. Finishing embellishments for the box are illustrated by the moldings 1, 2, 3, 4, 5, 6, 7 and 8.

Although the exact contour for the plan view of the box, as shown in Fig. 2, is specifically an isosceles trapezoid, the edges at 2 and 6 are relatively so short that the general effect is triangular rather than trapezoidal and is so contemplated in the design.

I claim:

The ornamental design for a phonograph box, or similar article, as shown and described.

WILLIAM WUTHENOW.

Witnesses:

W.M. J. SCHWEIGER,
L. ALTMAN.
